2 SHEETS—SHEET 2.

UNITED STATES PATENT OFFICE.

FREDERICK C. CROWE, OF YAKIMA, WASHINGTON, ASSIGNOR TO VARIETY MANUFACTURING COMPANY, OF YAKIMA, WASHINGTON.

BENDING MACHINE.

1,414,340.

Specification of Letters Patent. Patented May 2, 1922.

Application filed April 12, 1921. Serial No. 460,688.

To all whom it may concern:

Be it known that I, FREDERICK C. CROWE, a citizen of the United States, residing at Yakima, in Yakima County and State of Washington, have invented certain new and useful Improvements in Bending Machines, of which the following is a specification.

My present invention relates to improvements in bending machines adapted especially for the purpose of forming flanges in sheet metal blanks in the process of forming tubes, as stove pipes, or other tubular structures having a longitudinal seam for locking the adjoining edges in the completion of the pipe or tube. The primary object of the invention is the provision of a machine of this character that is comparatively simple in construction and operation, durable, and inexpensive in cost of manufacture. To this end the invention involves certain novel combinations and arrangements of parts involving progressive sets of bending rollers for successively bending the edges of a sheet of metal preparatory to interlocking the completed blank into tubular form, and in certain other novel features of construction as will be hereinafter more fully pointed out and claimed.

In the accompanying drawings I have illustrated one complete example of the physical embodiment of my invention wherein the parts are combined and arranged according to the best mode I have thus far devised for the practical application of the principles of my invention. It will be understood that the embodiment shown may be changed and altered as desired within the scope of my appended claims without departing from the spirit of my invention.

Figure 1 is a view in side elevation of a machine embodying my invention, with a portion of the frame at the near side of the machine removed for convenience of illustration.

Figure 2 is a top plan view of the operating parts of the machine.

Figure 3 is a front view of the machine with parts broken away, and part shown in section to disclose the arrangement of parts.

Figure 4 is an end view of one of a pair of guide dies or blocks for the edges of the sheet being bent in the machine.

Figures 5, 6 and 7 show diagrammatically the three sets of progressive bending rollers,

indicating their functions in the bending machine.

Figure 8 shows the concaved and convexed feed rolls to conform to the shape of the rolled pipe.

The preferred form of the invention as illustrated in the drawings is especially adapted for use in flanging or bending the complementary edges of a sheet metal plate that has previously been shaped to tubular form in order to provide the necessary interlocking flanges or bends that are subsequently laid or compressed into a seam, as for instance in the formation of a stove pipe, and while sheet metal may be bent in the machine for other uses, for convenience of description, the tube will be referred to hereinafter as a stove pipe, parts of which are indicated in Figures 6 and 7 of the drawings by the letter S.

The machine is supported on a main frame including the uprights 1, 1' and top plates 2, and the frame which is of suitable height and required strength, may be braced and fixed together in usual or well known manner. The previously bent or shaped sheet of metal is introduced to the machine presenting one end to the guide rollers 3, 4, and 5 with the complementary, longitudinally extending edges that are to be bent or flanged at the top, the body of the sheet being pushed over the horizontal, concave roller 5 and the two free edges of the sheet held or restrained by the enlarged, upper ends of the tapered and concave rollers 3 and 4 which are disposed in perpendicular position to the roller 5. Thus the three rollers guide the sheet of metal to the machine by means of which its longitudinal edges are flanged or bent for subsequent interlocking.

One of the cross or top plates 2 is utilized to support the upper ends of the vertical guide rollers, and angle brackets 6 and 7 are utilized to support the lower ends of these rollers, as well as to support the horizontal roller 5. The angle brackets are complementary and are bolted to the inner faces of the uprights 1, 1' of the frame, and the three rollers are adjustably supported each on a pair of bearing plates 8 which have journals 9 fixed therein, and the journals on which the rollers are fixed, pass through slots in the cross plate 2 and angled brackets 6 and 7 respectively.

The bearing plates which support the

journals of the guide rollers are secured to the cross plate and angle brackets by bolts 10, and the supports for these plates have each a series of bolt holes 11, one of which 5 may be selected for the attachment bolt 10, by means of which the relative position of the three rollers may be changed to adapt them for different diameters of tubular forms or pipes in the process of making. 10 The bearing plates may be slotted as at 44, 44 to allow an adjusting movement within the scope of the slots and the springs 45 engaging the bearings will keep the guide rolls adjusted to the lesser limit and provide a means whereby taper pipe may be 15 handled and properly guided. It will thus be apparent that the vertical rollers are adjustable laterally and the horizontal roller is adjustable vertically in their supporting 20 elements or members, and will automatically expand or separate as the diameter of the pipe increases.

The metal bending machinery is compactly arranged and supported in a central 25 housing 12 which, extending longitudinally of the machine, projects forward between the two vertical guide rollers and backward a suitable distance therefrom to support the progressive bending mechanisms. The machine is preferably actuated from a driving 30 gear 13 encased within the housing, the driven pulley 14 and shaft 15. The driving shaft 15 passes transversely through the housing and carries the driving gear 13, and 35 the shaft is journaled in bearings as at 16 on the main frame. The three sets of progressive bending rollers are designated respectively 17, 18 and 19, each set comprising two pairs and the pairs of the sets are 40 located at the respective sides and exterior of the centrally located housing, thus permitting the complementary edges of the tubular sheet of metal to pass along at the respective sides of the housing as the bending progresses.

The feed rolls and the sets of bending rollers are directly and positively operated from the driving gear 13 in the housing, the third set 19 having a pair of co-acting gears 50 and 21; the second set 18 having co-acting gears 22 and 23, both gear sets being driven from the driving gear 13. The driving gear also operates an idle gear 24 which drives the gear set 25, 26 of the first set of 55 bending rollers, and the gear 26 operates the idle gear 50 which drives the gear set 46, 47 of the feed rolls. The feed rolls which are used to convey the sheet metal pipe are placed in advance of the forming 60 rolls to engage the sheet metal and pass it on to the forming rolls and these feed rolls have concave edges on the bottom set 49 and are convex on the top set 48 to substantially conform to the curvature of the sheet metal, 65 the direction of rotation being indicated by

arrows in Figure 1 where the gears are indicated by dotted lines.

Thus all the rollers are timed and synchronized to exert the same traction or frictional engagement with the sheet metal 70 passing through the machine, and the progressive bending rollers also form the feed mechanism, operated from the driving shaft 15, for eliminating unequal stresses, and preventing buckling of the metal sheet in 75 its forward movement.

The first set of forming rollers as indicated in Figures 3 and 5 comprise a pair of upper, complementary double rollers 27, 27 and a complementary pair of flanged rollers 80 28, 28 which co-act to form a vertical, upwardly extending flange between rollers 27 and 28 at the left in Figure 5, and a vertical, downwardly extending flange between the reversely arranged rollers 27 and 28 at 85 the right side of the figure, these flanges being bent at right angles to a line tangential with the periphery of the tube being formed. As the forward end of the sheet passes through the first set of rollers the flanged 90 edges encounter a guide block or die 29, one attached at each exterior side of the housing in proper alignment to receive the flanged edges, and these blocks are fashioned with L-shaped slots 30 extending horizontally 95 therethrough, the right hand guide block in Figure 4 being adapted to receive the downwardly extending flange, and the left hand block having its slot shaped to receive the upwardly extending flange at the left of the 100 housing.

The sheet metal is fed forward by the first set of bending rollers, through the guide blocks 29 to the second set, where a more acute angle is imparted to the flanges, as 105 indicated in Figure 6. The second set of bending rollers include a pair of conical upper and lower rollers 31, 31 one at each side of the housing, which co-act with the complementary pair of inner beveled rollers 110 32, and in conjunction with this set of rollers I employ a pair of rotary anvils in the form of a horizontally disposed conical roller 33, and an angularly disposed conical roller 34, at opposite sides of the housing 115 and journaled in brackets secured to the housing. As the flanged edges of the metal sheet pass through these rollers, the flanges are bent in substantially the same plane, at acute angles to the tangential line of the 120 periphery of the tube being formed, as indicated at S in Figure 6.

The sheet is now being fed forward by the tractive force of the two sets of rollers 17 and 18, and the front end of the sheet 125 with its acutely formed flanges is introduced to the third and final set of bending rollers indicated as 19. This final set comprises a pair of upper and lower outwardly beveled rollers 35, 35 and a complementary 130

pair of flanged rollers 36, 36 having inwardly beveled faces, and by co-action of these beveled portions and flanges reversely formed offsets or grooves are fashioned 5 along the bent flanges of the edges in order that when the seam is subsequently laid in another machine, or by hand power, the periphery of the completed tube will present a smooth surface.

10 Thus by the action of the three sets of rollers, the metal sheet is passed through the machine and the edges flanged or bent to the desired formation to permit subsequently interlocking of the flanges to form 15 the seam.

The shafts of the rollers are designated by the numeral 37, and some of these shafts may have adjustable bearings, to take up wear, and to afford adjustment of the co- 20 acting rollers. Thus the housing may be slotted as at 38 to permit movement of the shafts, and the shafts of the upper rollers may be retained in adjustable bearing blocks 39 encased within the housing. These blocks 25 may be adjusted as to their altitude by screw bars 40, and clamped in proper position by clamp nuts 41 bearing on the top surface of the housing.

After the seaming or bending machine has 30 performed its functions as above described, the tubular sheet with its properly formed flanges may be formed into a completed tube and the seam laid as before indicated.

To insure accurate and rapid feeding of 35 the sheet metal pipe a tapered feed guide 42 is mounted on the central housing 12 with its upper edge or face in a direct horizontal line with the forming rolls at the point where the upper and lower rolls meet and 40 erected on this taper feed guide on the upper side thereof is a wedge plate 43 to separate the longitudinal edges of the pipe to a width to correspond to the width of the housing thus spacing the edges of the pipe so as to be 45 properly received by the forming rolls. This guide may be made of varying sizes to correspond with the various sizes of pipe.

Having thus fully described my invention, what I claim and desire to secure by Letters 50 Patent is—

1. The combination with a longitudinally disposed central housing, a driving pulley, shaft, and a driving gear on said shaft en- 55 cased in the housing, of feed rolls and progressive sets of bending rollers having transverse shafts in said housing and ar-

ranged at the sides of the housing, a gear set for each roller set actuated from the driving gear, guide rollers for introducing a sheet metal to the first roller set, and a feed guide for separating the edges of the sheet metal to be received by the forming rolls, as described.

2. The combination with a longitudinally disposed central housing of guide rollers 65 and progressive bending rollers supported therein and operating means for said rollers within the housing, each set of rollers comprising a pair of rollers at each side of the housing arranged in inverted relation where- 70 by oppositely extending flanges are formed along the proximate edges of a sheet of metal, for the purpose described.

3. The combination with a longitudinally disposed central housing, of progressive 75 bending rollers supported therein and operating means for said rollers within the housing, each set of rollers comprising a pair of rollers arranged in inverted order at op- 80 posite sides of the housing, one of said sets having a pair of co-acting, conical, anvil rollers, and means for operating said operating means whereby the sets of rollers are synchronously actuated, and an advance set of rollers to feed a metal sheet through said 85 sets.

4. The combination with a longitudinally disposed central housing, a drive shaft, a drive pulley and a drive gear thereon en- 90 cased by the housing, of progressive sets of bending rollers having transverse shafts in said housing, gears on said shafts actuated from the driving gear, adjustable bearing blocks for some of said shafts within the housing, means for holding said blocks in 95 adjusted position, and a pair of die blocks interposed between two sets of bending rollers.

5. The combination in a metal bending machine with adjustable, concave guide 100 rollers forming a circular space therebe- 105 tween, of a central, longitudinal housing and a driving gear therein suitably actuated, progressive sets of bending rollers and a set of feed rollers at the sides of said housing and connections thereto from the driving gear, and means for adjusting the bearings of some of said bending rollers, as de- scribed.

In testimony whereof I affix my signature. 110

FREDERICK C. CROWE.
